UNITED STATES PATENT OFFICE.

GEORGE F. ROOKE, OF PROVIDENCE, RHODE ISLAND, ASSIGNOR TO ROOKE AUTOMATIC REGISTER COMPANY, OF PROVIDENCE, RHODE ISLAND, A CORPORATION OF MAINE.

SELECTOR MECHANISM FOR REGISTERS.

Application filed July 6, 1922. Serial No. 573,131.

The present invention relates to machines for registering unit articles of various sorts or qualities, or the values of such articles, and the embodiment of it herein dis-

ticle of smaller value, will not register its 55 full value; and this invention has for its purpose to prevent a dishonest tally being so made.

5 closed is particularly adapted and designed for use with portable fare registers of the type disclosed in my prior patents granted February 11, 1919, and numbered respectively 1,294,307 and 1,294,308. The registers disclosed in said patents are provided with two counters, one of which is operated whenever a coin or ticket is placed in the machine, while the other is operated only when a coin or ticket of a 10 specific dimension is received. The mechanism which drives the second counter is made active, or caused to remain inactive, by means of an arm which is engaged by the circumference of the coin or ticket after the latter has been gripped by the grippers and has been propelled a certain distance by the carriage with which the machine is provided for gripping and propelling the ticket. The arm above referred to is called a selector and 15 is one embodiment of generic selector means for controlling the mode of action of a counter according to the value of a characteristic dimension of the coin or other article which may be placed in the machine.

20 One of the objects of the invention is to provide a selector mechanism of such a character and in such a position that it may be positioned immediately upon insertion of the article into the machine and prior to the

25 Although I have here particularly referred to coins and tickets, I wish it to be understood that this reference is for illustration and does not indicate any limitation in the utility or scope of the invention as to the particular articles tallied. Within the meaning of the term "ticket" I include any 30 standard coins, or tokens having an arbitrary value for counting purposes. Such tickets may be circular disks of metal, or they may have other shapes or be made of other materials. So far as the principles 35 of the invention are concerned, the essential factor is that the tickets or articles of whatever value, whether that value is standard or arbitrary for a particular purpose, should differ from one another in one dimension. 40 The selector mechanism is actuated or controlled by the surfaces of the article at the limits of this dimension, and controls the registering or tallying means so that the tally is made in proportion to the value 45 of the particular controlling article.

50 One of the objects of the invention is to

55 accomplish the above named objects consists of a pair of members which for the purpose of convenient identification in 60 this description, but without limiting intent, I call "selector fingers," arranged to receive between them the article inserted for 65 tallying in the register, and coupled to influence the registering mechanism according 70 to their position as governed by the dimension of the inserted article. Such fingers are mounted in a floating manner, that is, 75 in such fashion that they are freely movable and when either is moved by force applied 80 to it alone, the other is moved to substantially the same distance in the same direction, but, in order to change the distance 85 between them, both must be pressed upon or obstructed at the same time by forces 90 acting in relatively opposite directions. Since, when in use, the machine is entirely 95 enclosed in a protective casing which prevents access to the fingers except by the article to be tallied, inserted through the entrance in the casing provided for its reception, this means that, practically, the fingers 100 can be spaced apart only by such an article,

35 initiation of the movements which eventually cause operation of that counter, the operation of which is affected by the dimension of the article. Another object is to prevent dishonest setting of the selector

40 mechanism in such a way as to tally a lower value than that ascribed to the inserted article, or conversely to fail to tally the value of the article. When, as is generally the case with machines of the character referred

45 to, the purpose of the register is merely to tally the value of the articles inserted, or count the number of articles of different values, and not to retain them in a locked receptacle from which the custodian of the

50 machine or other attendant, is excluded, the custodian or attendant, is exposed to the temptation of so placing the selector that the article of larger value, when its characteristic dimension is less than that of an ar-

Such fingers and associated means for controlling the registering mechanism constitute the present invention. The embodiment of such invention herein illustrated is applied for controlling two independent counters in a machine which, except for the invention involved in such selector mechanism is the invention of Walter S. Johnson and is disclosed in applications filed by him on February 10, 1922, and serially numbered 535,571 and 535,572, and is not claimed by me.

It is to be understood that the principles and scope of the invention are not limited to the specific embodiment shown and described in this specification and that, therefore, in describing such embodiment my intention is to disclose one of the operative means for utilizing the invention, and that the same principles may be applied in other forms and in other environments within the scope of the protection which I here claim.

However, since the machine in which the invention is shown as being applied in the present specification is a portable register adapted to be used by a collector to receive cash fares or equivalent tickets from passengers on a public conveyance, and for similar purposes, I will generally in the following specification refer to the operator of the machine as the collector and to the person who deposits the coin, ticket, and so forth, as the passenger, for convenience of description and subject to the foregoing statements regarding the scope of the invention.

In the drawings,—

Figure 1 is a front elevation of the particular register referred to, such elevation showing only the working parts and omitting the enveloping casing by which such working parts are enclosed and protected in the actual use of the machine.

Figure 2 is an elevation of the selector mechanism and counter operating means separated from those parts of the machine which in Figure 1 obscure such mechanism.

Figure 3 is a view similar to Figure 1 but showing the parts in the position after registration has been effected.

Figure 4 is a view of the same parts shown in Figure 2 but in the same position as indicated in Figure 3.

Like reference characters designate the same parts wherever they occur in all the figures.

It will be understood that the entire machine hereinafter described, is enclosed in a protective casing, when in condition for use, as are the machines shown in the before mentioned prior patents. The casing is omitted from these drawings in order to simplify them; but the skilled mechanic or designer will readily understand under the teaching of said prior patents, in what man-

ner such casings may be fashioned and applied to machines of various designs embodying this invention.

The numeral 1 represents a relatively stationary frame which comprises members forming a substantially rectangular outline, and front and rear plates secured thereto. The parts numbered 2, 3 and 4 represent two side bars and the transverse top member of a carriage which is arranged to reciprocate in suitable guideways in the frame. To this carriage is attached a traction stud or pin 5 to which is coupled a tape or equivalent pulling member 6 wrapped around a barrel 7 which is pivoted on a pivot stud 8 secured to the frame and contains a spring 9. The function of the spring, barrel and tape is to draw the carriage suddenly from the position in which it is shown in Figure 1, this being the "set" or potentially operative position, to a different position represented in Figure 3. The carriage is latched in the set position and the latch is adapted to be released by a tripper shown by dotted lines at 12^a, which lies just within the slot, or other entrance opening, provided in the casing to receive the inserted ticket, and is in such position that the ticket, on being inserted in such slot, trips the latch and releases the carriage. Also positioned just within the slot are grippers 22 at opposite sides of the space entered by the ticket, and carried by levers, one of which is shown at 18, which are operated to grip the tickets as soon as the carriage begins to move after being unlatched. The parts just mentioned are substantially like the means disclosed in my prior Patent No. 1,294,303 for setting, latching, and tripping the carriage and for gripping and releasing the tickets, wherefore they are not fully illustrated herein, but reference is directed to said prior patent for explanation of the subject-matter thus omitted.

The two counters for registering or tallying the values of tickets are shown at 25 and 26. These may be any suitable sort of counters having number indicating mechanism, of which that of the counter 25 is operated by a pinion 27 and that of the counter 26 is operated by a shaft 28 carrying an arm 29. Pinion 27 meshes with a driving gear wheel 30 having a hub 30^a mounted on a stud 31 fixed to the frame, and such gear wheel is driven by a driving pawl 33 pivoted upon a pawl carrier 32 which turns about the stud 31. A pin 37 connected to the pawl carrier, in a manner which is not material to the present invention, projects to the rear of such carrier for the purpose of receiving driving impulses from the carriage.

Such driving impulses are applied by the traction stud 5 of the carriage through a cam lever 40 or driver and a transmission member or plate 41, such plate being pivoted to the lever by a pin 42, and the lever being piv-

oted to the frame on a pin 42^a. The traction pin of the carriage travels in a slot 43 of the lever, the lower end of which slot is offset so as to act as a cam when the carriage 5 approaches the end of its travel, to displace the lever and transmission plate from the position shown in Figures 1 and 2 to that shown in Figures 3 and 4.

The counter 25 is adapted to tally tickets 10 of different values in terms of a unit value and multiples thereof, wherefore the transmission plate 41 is provided with a series of opposed abutments adapted to be selectively placed in operative relation with the pin 37. 15 Placement of the various abutments in operative relation is effected by the selector mechanism of this invention. Those abutments which operate the driving pawl in driving the counter are designated 45, 46 and 47, while the opposed abutment, which returns the pawl to starting position, is shown at 44. The abutments 45, 46 and 47 are differently distant from the abutment 44 in order to provide for different amounts of lost 20 motion when respectively placed in operative relation with the pin 37. The abutment 46 operates when a ticket of smallest value is inserted and gives only enough movement to the driving pawl to cause tallying of one 25 unit; while the abutment 47, permitting a shorter lost motion, gives a greater movement to the counter so as to register two or more units; and the abutment 45, providing no lost motion, gives the maximum actuation 30 to the counter and so causes registration of the highest multiple of the unit value which that counter is adapted to register. Besides the abutments there is a notch 48 permitting lost motion great enough to consume the entire movement of the transmission plate without operating the counter; thus permitting the counter 25 to remain inoperative when a ticket of the denomination 40 which operates the other counter 26 is inserted. 45

The operating arm 29 of the counter 26 is oscillated under control of the selective mechanism, to actuate this counter, when the counter 25 remains inoperative; and conversely it remains inoperative when counter 50 25 is operated. A transmission member or coupling 49 is pivoted to the cam lever 40 at 50 and has a pin 51 which enters an opening 52 in lever 29. Part of the opening 52 is relatively wide and another part is narrow, and the pin 51 is shifted into one part or the other by the selector mechanism. When in the narrow part of the opening it actuates the counter, and when in the wide part thereof it imparts no motion thereto.

The selector mechanism for controlling the transmission members 41 and 49 in the manner and to the end above indicated, and in which my present invention is embodied, 60 65 comprises a pair of floating fingers 57 and

58, a selector 59, and a selector lock 60. The selector as developed in the embodiment here illustrated is a bar or plate having slots 61 through which pass two supporting pins 62, 63, fixed to the base, on which the selector 70 rests and over which it is retained by a retainer 64 suitably interlocked with the pins. This selector is thus adapted to slide endwise. It is normally retained at one end of its movement by a spring 65 surrounding 75 the hub 30^a of the driving gear 30 and reacting on a fixed stud 66. The selector is coupled with the transmission plate 41 by a pin 69 on the latter which enters an upright slot 68 in the former. According as the selector 80 is moved to a greater or less extent from the normal position it places the abutment 45, or 46 or 47, or the notch 48, in line with the actuating pin 37; and it is retained in either of these positions by the selector lock 60 85 coacting with one or another of the teeth or projections 70 on the selector. When in that extreme position which makes the counter 25 inoperative, by putting notch 48 in line with pin 37, the selector puts the 90 transmission coupling 49 in position to operate the counter 26, through engagement of a lug 71 on the selector with an abutment 99 on said transmission coupling, as will be 95 apparent by comparing Figures 1 and 3.

The floating fingers 57 and 58 are arranged at opposite sides of the entrance passage in which the ticket is inserted. When the machine is enclosed within its protecting casing, in condition for use, these fingers are just within the entrance slot of the casing and near opposite ends thereof and in a position to be engaged by the ticket before the latter trips the carriage. Normally they are separated from one another by a distance 100 substantially equal to the width of the smallest ticket or coin which the machine is intended to receive, and they are adapted to be spread more widely apart by a ticket of 105 larger dimension. The finger 57 is carried by a lever 72 which is pivoted to the frame on a stud 73 and has a second arm 74. The finger 58 is carried by an arm 75 which is pivoted to the frame on a stud 76. Such arm 75 and lever arm 74 are connected to one 110 another and to the selector slide by a lever 77 pivoted to the arm 75 by a pin 78, to the selector slide by a pin 79, and to the lever arm 74 by a pin 80. Slots 81 and 82 are cut in the lever 77 to receive the pins 79 and 80 115 and to permit endwise movement of such pins relatively to the lever on account of the divergence of the paths wherein such pins and the contiguous parts of the lever move.

Now, if the fingers are spread apart from 120 their position of closest approach, that shown in Figure 1, the lever 77 gives to the selector bar 59 a movement which is substantially equal to the increase in distance 125 between the fingers (in the construction here 130

shown) and may be greater or less than this distance, according as the pin 80 is placed nearer to the pin 78 or nearer to the pin 79. One important feature of this mechanism is the fact that it enables the increments of movement given to the selector by the tickets of progressively increasing widths to be great enough for accurately placing and locking the selector so as to tally correctly the values of the various tickets. To explain further I may say that in many instances, and particularly where it is desired to cause the same register to tally a relatively large number of tickets of different values, including standard coins, the permissible differences in diameter between some of the coins and tickets in the series is very small; at least so small as to make difficult the correct positioning and securing of the selector if the corresponding step in the movement given to the latter were less than the difference between the tickets. The construction of finger control just described obviates this difficulty by enabling the movement given to the selector bar to be equal to, or even greater than, the difference between the successive tickets, thus enabling the complementary locking teeth of the selector and lock to be wide enough for adequate strength and placed far enough apart to ensure correct positioning and locking in the time available for that function when the machine operates. Inasmuch as the transmission lever 77 is pivoted to both finger levers, the same resultant movement is given to the selector bar, whether the spreading movement between the fingers is accomplished by the movement of either finger alone away from the other, or of both fingers in relatively opposite directions at the same time.

The spring 65 which acts on the selector, as previously described, constantly tends to return the fingers to their position of closest approach, and retains them in this position at all times except when they are spread apart by a wider ticket.

If pressure is applied to either of the fingers alone away from the other, and the latter is not restrained at the same time, both fingers move together through substantially the same distance, because then the pivot 79 is a stationary fulcrum and the lever 77 becomes a means for transmitting movement from one finger to the other. Under conditions of use it is impossible for the distance between the fingers to be increased otherwise than by simultaneous pressure of the inserted ticket against both fingers, owing to the fact that the casing prevents blocking or restraint of either finger by other means. That is, it is impossible for a dishonest collector, or a person paying a fare and being in collusion with the collector, to increase the spreading of the fingers by pressing the ticket against one finger alone. The tempta-

tion to do this occurs when a machine is set for registering nickel five cent pieces and silver dimes, or any other case in which the coin or ticket of larger diameter has the lower value, and if the fingers could be thus placed by a dishonest operator, so that they would be spread apart to the width of the lower value piece when the smaller piece of higher value is inserted, opportunity for fraud would be given.

It will be noted that the fingers project above the ticket grippers 22 and above the latch tripper 12^a, from which it follows that the selector mechanism is set in accordance with the size of the ticket before the carriage is released and the grippers are caused to grip the ticket.

The mode of operation of this machine is substantially identical with that described in my Patent No. 1,294,308 aforesaid, except as to the features involved in the present invention and those of the Johnson invention hereinbefore identified with which my present invention has been combined and which are herein illustrated as the operative environment of my said invention. The carriage is first put in the position shown in Figure 1, which may be called the "set" position, by the action of a plunger or rack bar 15 operating through mechanism substantially like that described in said patent; and it is retained in such position by a latch. In that position the tape 6 is drawn away from the drum 8 and the spring 9 is put under tension. At that time the driving stud 5 occupies the upper end of the slot 43 in the lever 40, holding said cam lever 40 in its raised position, and also occupies a notch 85 in the arm 83, allowing the spring 92 of the selector lock 60 to hold said lock in the inoperative position in respect to the selector 59. When a ticket is placed in the entrance slot of the machine, it passes between the fingers 57 and 58, first spreading said fingers apart, if its diameter is wider than the normal minimum distance between the fingers, and then displacing the latch tripper 12^a. Said latch tripper acts in the manner described in said Patent No. 1,294,308 to release the carriage, which is now moved downward by the pull of the spring 9. In this movement of the carriage the grippers 22 or the levers 18 are caused by mechanism essentially like that shown in said prior patent to grip the ticket and carry it with the carriage.

With the first part of this movement, the driving stud 5 swings the arm 83 of the selector lock to the left (with respect to these drawings) by pressing against the lower edge of the notch 85 and in so doing swings the lock 60 into connection with that one of the teeth 70 which has been placed according to the separation of the selector fingers in position to be engaged with the lock.

In the last part of the travel of the car-

riage, the stud enters the offset part of slot 43 and moves the cam lever 40 downward, thereby causing an addition to be made upon either the counter 25 or the counter 26, according to whether one or the other of the transmission members 41 or 49 has been made operative by the selector mechanism. If the selector mechanism has been placed or left in such a position that the counter 25 is operated, either of three different additions are tallied thereon according as the abutment 45, or 46, or 47 has been placed in position to act on the pin 37.

I desire to state that my invention and the protection which I claim for it are not limited to the details of construction or of coaction with the counting mechanism here shown. Neither is the broad invention limited to the case in which the fingers are normally at the minimum distance apart and are spread to a greater distance by tickets of all except the smallest width. On the contrary it is within my contemplation to provide, and I have provided, means by which the equivalent of the fingers here shown are normally arranged at the greatest distance apart and are released, so as to spring together, when a ticket is inserted, whereby to set the mechanism correctly for tickets of less than the greatest width.

What I claim and desire to secure by Letters Patent is:

1. In a register adapted to receive articles differing from one another in a characteristic dimension and comprising a counter and means for operating said counter when such an article is put into the register, a selective mechanism including relatively movable connected members, which are also movable in unison in the same direction as their relative movement, arranged and operable to engage said articles at opposite ends of such characteristic dimension for controlling the mode of action of said counter operating means.

2. In a register, the combination with selector fingers between which an inserted article is passed, said fingers being arranged to engage the surfaces of such article at opposite ends of one of its dimensions and mounted for movement in unison and also relatively to one another in opposite directions transverse to the entrance path of such an article, of counting means, counter-operating mechanism adapted to be variously set, and means operated by a change in the distance apart of said fingers from one another to set said operating means in accordance with the dimension of the inserted article.

3. In a register having counting mechanism and means for operating the same adapted to be set in different adjustments, a selective mechanism for setting said operating mechanism and including a pair of floating fingers between which the article to be registered is inserted, and connections oper-

ated by relative movement only between said fingers for so adjusting said operating mechanism.

4. In a register having counting mechanism and means for operating the same adapted to be set in different adjustments, a selective mechanism for setting said operating mechanism and including a pair of floating fingers between which the article to be registered is inserted, and connections operated by relative movement only between said fingers for so adjusting said operating mechanism, said fingers being so arranged that movement imparted to one of them alone causes approximately equal movement in the same direction of the other.

5. In a register, a selector mechanism consisting of fingers arranged to receive an inserted article between them and being pivotally mounted, a lever connected to both of said fingers in such manner that movement imparted to one finger alone causes substantially equal movement in the same direction to be imparted to the other, and separation or approach of the fingers with respect to one another causes a different movement to be given to said lever, counting means, and controlling means operated by the last-named movement of said lever causing a difference in the mode of action of said counting mechanism according to the distance of the fingers apart from one another.

6. A selector mechanism for a register comprising fingers located at opposite sides of the path in which an article to be tallied is inserted in the register, means supporting said fingers with provision for their free movement from side to side in their common plane, a lever pivotally connected with both fingers at separated points, and a shiftable selector connected to said lever at a third point.

7. In a register, a selector mechanism comprising pivotally mounted arms adapted to rock about substantially parallel axes, fingers carried by said arms and arranged on opposite sides of the passage in which an article to be tallied by the register is inserted, one of said arms having a second arm, a lever pivoted to the other of the first-named arms and to said second arm, and a selector pivotally connected to said lever and being movable in a prescribed path.

8. In a register having a passage for insertion of articles differing from one another in a characteristic dimension, the combination with counting means and operating means therefor variously placeable in different settings, of a selector mechanism for placing said operating means in different positions according to the characteristic dimension of the various articles and comprising a selector movable in a prescribed path and engaging said operating means, fingers arranged to embrace the inserted

article at the ends of the characteristic dimension thereof, and connections between said fingers and said selector constructed to shift the latter when the distance between the fingers is altered, and cause movement substantially in unison of the fingers, without shifting said selector, when movement causing force is applied to either finger alone.

10 9. In a register having a passage for insertion of articles differing from one another in a characteristic dimension, the combination with counting means and operating means therefor variously placeable in different settings, of a selector mechanism for placing said operating means in different positions according to the characteristic dimension of the various articles and comprising movably mounted fingers arranged to 20 embrace the inserted article at the ends of the characteristic dimension thereof, and a coupling member having connections with said fingers and with said operating means, so arranged that movement of the fingers toward or away from one another causes alteration in the placement of said means, but movement imparted to either finger alone causes movement of the other finger substantially in unison therewith and without dis- 30 placement of the operating means.

10 10. In a register having a passage for insertion of articles differing from one another in a characteristic dimension, the combination with counting means and operating means therefor variously placeable in different settings, of a selector mechanism for placing said operating means in different positions according to the characteristic dimension of the various articles and comprising pivotally mounted fingers adapted to embrace the inserted article at the ends of the characteristic dimension thereof, an arm rigidly connected with one of the fingers and extending toward the other finger, and 40 a coupling member pivoted to said other finger near its engaging point and to said arm at a point near the line between the engaging point and pivot of said other finger, said coupling having a pivotal connection at a point which is moved when relative motion between the fingers occurs and is substantially stationary when the fingers move in unison, said connection being operatively arranged to shift the operating means. 50

55 11. In a register of the character described, the combination with a counter, counter driving means and a selector movable to place said driving means in different settings, of cooperating floating selector members between which the articles to be tallied may be passed, such members being coupled together so as to move in unison when motion-causing force is applied to either of them singly, and being relatively movable together 60 and apart so as to engage opposite points

on such an article, whereby the distance between them is gaged by a dimension of the article, and connecting means between said members and selector constructed and arranged to impart to the selector a movement substantially as great as the movement made by said members. 70

12. A selector mechanism for a register of the character described comprising complementary members between which an article to be registered is passed, each of which members is movable toward and away from the other in directions transverse to the path of the inserted article and is adapted to occupy a position at a distance therefrom equal to a characteristic dimension of such article, a selector coupled to said members so as to be moved thereby, when the distance between the members is changed, through distances substantially equal to such changes, 80 a lock for holding said selector in any one of a number of different positions, counting means, and mechanism for operating said counting means placeable in different positions by said selector. 85

13. In a register, a pair of members arranged in position for the thing to be registered to pass between them, said members being freely movable, connecting means between said members arranged to cause movement imparted independently to one of the members to be transmitted in approximately equal degree to the other member, and a selective device coupled to said connecting means in such manner as to remain stationary when the members are moved in unison and to be shifted when either or both of the members are moved in a manner to change the distance between them. 95

14. In a machine of the nature set forth, a selective mechanism comprising arms pivoted to swing in approximately the same plane and having engaging portions adapted to receive a ticket between them and to be engaged by the opposite edges of the ticket, one of said arms having a second arm, a connecting lever having a pivotal connection with said second arm and with the other of the first named arms, and a selector member pivotally connected to and movable by said lever. 105

15. A selector mechanism for a register adapted to be set by an inserted ticket and comprising members located at opposite sides of and adjacent to the entrance through which the ticket to be registered is inserted, means supporting said members with provision for their free movement from side to side in their common plane, a lever pivotally connected with both members at separate points, which points are in a line transverse to the directions of permitted movement of the members, and a shiftable selector connected to said lever at a different point. 120

16. The combination in a selective mech- 125

anism for a register of a movable selector element, ticket engaging members arranged to move in directions approximately parallel to the prescribed movements of the selector, and a lever having pivoted points of connection with both ticket engaging elements and with said selector, the said pivot points being approximately in a line transverse to the prescribed movements of the selector and ticket engaging members.

17. In a register the combination with a counter and variable transmission mechanism for operating said counter, of means for setting said transmission mechanism con-

sisting of members between which the ticket 15 is passed in being placed in the machine, and connections between said members and said transmission mechanism adapted to move the latter when said members are so moved as to increase or diminish the distance 20 between them, and operable to move either of said members in approximate unison with the other of said members when pressure tending to move it is applied to one of said members alone.

25 In testimony whereof I have affixed my signature.

GEORGE F. ROOKE.
